UNITED STATES PATENT OFFICE.

JOHN FREDERICK LIEBENTRITT, OF BANKSTOWN, NEAR SYDNEY, NEW SOUTH WALES, AUSTRALIA.

MULTIPLE PUMP.

No. 848,836.

Specification of Letters Patent.

Patented April 2, 1907.

Application filed July 18, 1905. Serial No. 270,230.

To all whom it may concern:

Be it known that I, JOHN FREDERICK LIEBENTRITT, of Cumberland Pottery, Bankstown, near Sydney, in the State of New South Wales and Commonwealth of Australia, pottery and tile manufacturer, have invented an Improved Multiple Pump, of which the following is a specification.

This invention relates to an improved multiple pump wherein a series of barrels are arranged circularly and the pistons are actuated by the revolution of a cross-bar or handles similarly to a windlass around the geometric center of the circle of barrels and wherein the elasticity of a comparatively large body of air is utilized to assist the power applied; but in order that this invention may be clearly understood reference will now be made to the drawings herewith, in which—

Figure 1 is a plan of this improved multiple pump complete. Fig. 2 is a partial sectional plan of the same through the pump-barrels, showing also suction-valves and suction-ports. Fig. 3 is a sectional central elevation, and Fig. 4 is an enlarged detail of the pump piston or plunger.

The pump-barrels 4 are arranged circularly within a casing or air-chamber 5, having a bottom 6 and a top 7, the whole being air-tightly jointed. The top and bottom have, preferably, a stay-bolt 8 between them. Each barrel terminates at bottom in an air-chamber 31, having a discharge clack or valve 9 opening into the air-chamber 5 and a suction clack or valve 10 connected to the source of supply, say, by pipe or bend 32 to a box 33 and suction-pipe 34. In each barrel is a piston 11 with leathers 12, preferably at top and at bottom. The top part and bolt of this piston or plunger 11 is made in two halves, sweated together with a ring shrunk around the top and so firmly securing the head or knuckle joint 13 of rod 14, connected, preferably, by a universal joint 15 to the actuating plate or disk 16. This plate is held by collars 17 loosely on a spindle 18, whose lower end is the ball 19 of a universal joint made up on the two halves of a receiving-boss 21, secured together by bolts 20 and bolting to the top 7 of the air-chamber 5. The spindle 18 extends upwardly into a flat portion 24, taking in a slot or keeper 25 in the operating cross-bar 26. The slot 27 in

said spindle 18 is adapted to be placed in juxtaposition with one or other of a series of bolt-holes in the keeper 25, and to thus enable the spindle 18 and the disk 16 to be fixed in the desired inclined position or to be fixed normally out of operative position. The cross-bar 26 has fixed thereon rollers or runners 28 on the superimposed annular rail 29, supported by legs or standards 23 from the air-chamber top 7, and it has operating extensions or handles 30 outwardly of said runners 28.

In operation men or draft-animals walk around the multiple pump pushing or pulling the handles 30, and so causing the cross-bar 26 to revolve around its center, which is in line with the center of the circle in which the barrels 4 are arranged. When the spindle 18 is in the same center line, said disk 16, and consequently the pumps, are not operated. When, however, the spindle 18 is inclined, as shown in Fig. 3, it has motion upon its ball 19, around the center of said ball. The disk 16 is held free to revolve on spindle 18 between the collars 17 and is assisted by antifriction-rollers 22. Said disks 16 dips and rises in turn at every point in its circumference. By utilizing other of the bolt-holes in the keeper 25 the extent of this dip and rise may be adjusted, and consequently the stroke of the pump-pistons be regulated. As this actuating-disk 16 dips and rises the pistons 11 are each in turn reciprocated in the barrels 4, causing the necessary suction and discharge. The discharge is through valves 10 and 9 into the chamber 5, in which becomes imprisoned a large body of air whose elasticity is thus utilized to give evenness of discharge through the general exit or discharge pipe 35 and to assist in the working of the pump.

Having now particularly described and ascertained the nature of my said invention and in what manner the same is to be performed, I declare that what I claim is—

1. A multiple pump comprising a circular series of pump-barrels, pistons operating in the barrels, an inclined spindle, an inclined disk mounted on the spindle and connected with the pistons, a rotary operating device eccentrically connected with the spindle, and means for adjusting the spindle to change the inclination thereof.
2. A multiple pump embodying a circular

series of pump-barrels, pistons operating in the barrels, an inclined spindle, an actuating disk or plate mounted on the spindle and connected with the pistons, and a rotary operating device, said spindle being adjustably connected with the operating device and movable toward and from the center thereof, whereby the inclination of the spindle is changed.

- 10 3. A multiple pump embodying a casing, a plurality of pump-barrels, pistons operating in the barrels, a superimposed annular track, a rotary operating device mounted on the track, an inclined spindle eccentrically connected with the rotary operating device, and an inclined disk or plate mounted on the spindle and connected with the pistons.
- 15 4. A multiple pump comprising a plurality

of pump-barrels, pistons operating in the barrels, a superimposed annular track, an operating cross-bar arranged diametrically of the track and mounted thereon at opposite sides thereof and provided with a slot, an inclined spindle adjustably secured in the slot of the cross-bar and movable toward and from the center to change its inclination, and a plate or disk mounted on the spindle and connected with the pistons.

In testimony whereof I have signed my name to this specification in the presence of 3 two subscribing witnesses.

JOHN FREDERICK LIEBENTRITT.
